[73] Assignee: **Allied-Signal Inc.**, Morristown, N.J.

[57] CLAIM

[**] Term: **14 Years**

The ornamental design for a front partition for a tandem brake booster, as shown and described.

[21] Appl. No.: **994,186**

DESCRIPTION

[22] Filed: **Dec. 21, 1992**

FIG. 1 is a front elevation view of a front partition for a tandem brake booster showing our new design;
FIG. 2 is a side elevation view thereof, the opposite side being a mirror image of that shown;
FIG. 3 is a rear elevation view thereof;
FIG. 4 is a front perspective view of the partition plate of FIG. 1; and,
FIG. 5 is a rear perspective view thereof.
